UNITED STATES PATENT OFFICE.

NORMAN H. LOVEGROVE, OF SEATTLE, WASHINGTON.

DESIGN FOR A FINGER-RING.

51,682.

Specification for Design.

Patented Jan. 8, 1918.

Application filed October 15, 1917. Serial No. 196,764. Term of patent 3½ years.

To all whom it may concern:

Be it known that I, NORMAN H. LOVEGROVE, a citizen of the United States, residing at Seattle, in the county of King and State of Washington, have invented a new, original, and ornamental Design for Finger Rings, of which the following is a specification, reference being had to the accompanying drawings, forming part thereof.

Figure 1 is a plan view of a finger ring

showing my new design. Fig. 2 is a side elevation of same.

I claim:

The ornamental design for a finger ring, as shown.

NORMAN H. LOVEGROVE

Witnesses:

FRED P. GORIN,
MARGUERITE LEYDA.
